Patented May 24, 1927.

UNITED STATES PATENT OFFICE.

WILLIAM E. WULFHORST, OF CINCINNATI, OHIO.

AUTOMATIC SIGNAL.

Application filed July 1, 1924. Serial No. 723,493.

My invention relates to signals particularly though not exclusively adapted for use on street cars.

The objects of my invention are to provide means adapted to automatically signal persons behind a street car that the car is reducing its speed or that the car is traveling forward without immediate prospects of stopping; and to provide means adapted to automatically signal persons behind a street car that a passenger within the car has pressed a usual button and conveyed his desire to the motorman to alight from the car at the next stop, which signal is intended to convey information to persons behind the street car that the car is about to slacken its speed and stop.

My invention consists in providing means adapted to automatically connect and disconnect electric circuits for the purpose of illuminating signals intended to convey information regarding the immediate movement of the street car upon which said signals are displayed.

My invention further consists in the combination, location and arrangement of parts as herein specified and claimed.

In the drawings:

Fig. 1 is a partial rear elevation of a street car showing my invention embodied thereon;

Fig. 2 is a partial vertical section of a street car showing my diagrammatical disclosure of my invention embodied therein; and

Fig. 3 is a diagrammatical view showing the electric connections and means for automatically making and breaking said connections.

In the preferred construction of my invention, I provide spindle 1 journaled in bearings 2 and 3 suitably fixed to frame 4 of street car 5. Shoulders 6 and 7, respectively, of the spindle are adapted to engage the inner sides of bearings 2 and 3 for the purpose of retaining the spindle against longitudinal movement relative to the bearings. Belt 8 is combinedly received around end 9 of spindle 1 and axle 10 of wheel 11 of street car 5 whereby the spindle is adapted to be rotated at a speed directly dependent upon the velocity of the street car. The governor 12 has collar 13 fixed to spindle 1 adjacent bearing 2. Collar 14 of the governor is slidably mounted on the spindle and has commutator 15 fixed thereto

and slidably mounted on the spindle whereby the position of the commutator is dependent upon the speed at which the spindle rotates, as by collar 14 of the governor 60 moving inwardly or outwardly caused by the well known principles of centrifugal force of weights 16 of the governor exerting an outwardly pulling force when the governor is rotated. Commutator 15 is 65 preferably of non-conducting material cylindrical in form and has electric conducting band 15' around the central portion thereof. Tension spring 17 around spindle 1 has ends 17' and 17", respectively, fixed 70 to collars 13 and 14 of the governor whereby collar 14 is adapted to slide longitudinally on spindle 1 and away from collar 13 when the spindle is not rotating or the 75 rotatable speed of the spindle is slackened sufficiently to permit the tension force of spring 17 to overcome the centrifugal force of weights 16.

Terminals 18 and 18', suitably fixed adjacent commutator 15 and spaced apart therefrom, are adapted to be contacted by electric conducting band 15'. Terminal 18 is connected with green lamp 19 by conductor 20. Conductor 21 connects terminal 18' with terminal 22 adjacent commutator 23 and oppositely disposed from terminal 22' connected to knife switch 25 by conductor 41 and main conductor 24. The knife switch has connection with suitable outside source of electric current through conductors 25' 80 and 25" such as trolley wires (not shown). Commutator 23 has electric conducting band 26 therearound and adapted to be contacted simultaneously by terminals 22 and 22'. Bar 27 positioned within solenoid 28 85 has its inner end fixed to commutator 23 for the purpose of automatically making and breaking electric contact of terminals 22 and 22' with band 26 of the commutator depending upon the amount of current flowing through the solenoid. Conductor 29 combinedly connected to green lamp 19 and to knife switch 25 (through main conductor 30) comprises the remainder of the green lamp electric circuit, the operation of which 90 will hereinafter be explained.

Oppositely disposed terminals 31 and 31' adjacent commutator 15 are adapted to contact conducting band 15' and are respectively connected to conductor 32 (connected to red lamp 33) and main conductor 30' (connected to main conductor 30). The electric 100 105 110

circuit of the red lamp is completed by conductor 34 being connected to main conductor 24.

The electric circuit of caution lamp 35 comprises conductor 36 combinedly connected to the lamp and main conductor 30, conductor 37 combinedly connected to the lamp and terminal 38, conducting band 26, terminal 38', conductor 41', conductor 41 and main conductor 24. Conducting band 26 is adapted to simultaneously contact terminals 38 and 38' caused by bar 39 within solenoid 40 having one end fixed to commutator 23 whereby the caution lamp circuit is automatically completed and continues from terminal 38' to conductor 41 combinedly connected to conductor 41' (connected to terminal 38) and main conductor 34.

The flow of electric current through solenoid 40 by which magnetic lines of force are set up and causes bar 39 within the solenoid to move inwardly for the purpose of connecting conducting band 26 with terminals 38 and 38' for completing the electric circuit of caution lamp 35, is caused by manual operation of press button 42 which simultaneously actuates buzzer 43 advantageously positioned for signaling the motorman of street car 5 that a passenger within the car has expressed his desire to alight from the street car at the next stop. Electric current flowing from main conductor 24 through primary coil 44 of transformer 45 induces current in secondary coil 46 at an increased or reduced voltage dependent upon the winding of the transformer. For illustrative purposes main conductor 24 is shown as a 110 volt line and the current induced in secondary coil 46 preferably is 6 volts for the purpose of actuating buzzer 43. The electric circuit completed by manually pressing or operating button 42 comprises secondary coil 46, conductor 46', conductor 48, press button 42, conductor 42', buzzer 43, conductor 43', and conductor 50.

As heretofore explained, one of the objects of applicant's invention is to provide means adapted to signal persons behind a street car that the car is about to stop when a person within the car presses button 42, whereby caution lamp 35 is caused to light thereby performing its intended function of signaling persons behind street car 5 that the car is about to stop. Caution lamp 35 may be of any suitable color and the indicia or character designations may be illuminated by it for the purposes intended.

When street car 5 has sufficiently reduced its velocity (after button 42 is pressed), to permit the tension in spring 17 around spindle 1 to overcome the centrifugal force of rotating weights 16 of governor 12, collar 14 slidably mounted on spindle 1 and having commutator 15 fixed thereto, is slid longitudinally on the spindle thereby contact-

ing terminals 47 and 47' (positioned intermediate terminals 18, 18' and 31 and 31', respectively, and oppositely disposed relative to commutator 15) with conducting band 15' of commutator 15 whereby an electric circuit is completed and which comprises conductors 48 and 49 (respectively fixed to terminals 47 and 47') secondary coil 46, conductors 50 and 51 and solenoid 28, whereby the magnetic lines of force set up in the solenoid are sufficient to draw bar 27 outwardly thereby disconnecting terminals 38 and 38' from conducting band 26 of commutator 23, and connecting conducting band 26 with terminals 22 and 22'. During the last operation and when bar 27 is drawn inwardly and disconnects conducting band 26 from terminals 38 and 38', caution lamp 35 is extinguished. As the car continues to slacken its velocity, governor 12 gradually closes and slides conducting band 15' of commutator 15 into contact with terminals 31 and 31' thereby completing the electric circuit, heretofore explained, for lighting stop or red lamp 35. It is apparent that the distance from terminals 47 and 47', respectively, to terminals 31 and 31' may be varied for the purpose of causing red lamp 33 to light almost instantly or a considerable period of time after caution lamp 35 is extinguished.

Red lamp 33 is adapted to light during the latter portion of the time the car is stopping and while it is at a standstill. When street car 5 starts rearward or forward movement from a standstill, belt 8 combinedly received by spindle 1 and axle 10, imparts rotary movement to the spindle thereby causing governor 12 to gradually open, and conducting band 15' of commutator 15 to slide from contact with terminals 31 and 31' thereby breaking the electric circuit of lamp 35 and extinguishing the lamp. As the velocity of the car increases, commutator 15 is caused to slide a distance farther dependent upon the speed of the car, until conducting band 15' contacts terminals 47 and 47' whereby, through the electric circuit heretofore explained, magnetic lines of force are set up in solenoid 28 thereby causing bar 27 to draw conducting band 26 of commutator 23 in contact with terminals 22 and 22', which partly completes the electric circuit of green lamp 19. Further increased velocity of the street car causes the governor to continue to open and slide commutator 15 on spindle 1 until conductive band 15' contacts terminals 18 and 18' thereby causing green lamp 19 to light by completing the electric circuit heretofore explained.

Green lamp 19 remains lighted continuously during the time street car 5 is traveling forward at full speed without immediate prospects of stopping, and when a passenger, within the street car, presses a usual

button 42 for the purpose of signaling the motorman that it is the passenger's desire to alight at the next stop, green lamp 19 is immediately extinguished and caution lamp 35 is caused to light, thereby signaling persons behind the street car that the car is about to slacken its speed and stop. When the velocity of the car is slackened to a predetermined speed, caution lamp 35 is extinguished and red lamp 33 is lighted to warn persons behind the car that the car is moving at low velocity and is coming to a standstill. The red lamp 33 remains lighted during the time the street car is stopped and after starting until the car has attained a predetermined rate of velocity, at which time red lamp 33 is extinguished and green lamp 19 is lighted. Green lamp 19, red lamp 33 and caution lamp 35 may be positioned at any advantageous and desirable position, and in any preferred arrangement on the rear end 52 of street car 5. In Fig. 1 an arrangement of the lamps is shown in which green lamp 19 is positioned intermediate red lamp 33 and caution lamp 35. The lamps may be variously arranged and secured to the street car in any suitable manner.

The operations of my invention are automatic and it is apparent that I have invented a practical, efficient and highly desirable device for the purposes intended.

While I have shown and described my invention as embodied in a street car, my automatic signals may be incorporated in the construction of other and all types of vehicles. In some cases slight modifications of the wiring and construction may be necessary.

An advantage of my invention is in the provision of an automatic signal device adapted to impart knowledge to persons behind the moving street car or automobile having my invention embodied therein, that the vehicle is moving forward without immediate prospects of slackening its velocity or that it is slackening its velocity for the purpose of stopping or that it is almost stopped or that it is at a complete standstill. At this day and age of modern achievement and when the streets of our cities are overcrowded with rapidly moving vehicles, my automatic signaling device is adapted to greatly facilitate the movement of traffic as well as greatly reduce the chances of collision and accident as the result of vehicles suddenly stopping without warning to persons in the rear.

While I have chosen to illustrate the form and construction of my invention as herein set forth, I do not include the various forms of modification in which my invention may be incorporated. The illustrations and explanations herein are made merely for the purpose of showing a form of construction

by which my invention may be carried into effect.

My invention resides in the combination and arrangement of parts and in the details of construction, as hereinafter claimed, it being understood that changes in the precise embodiment of the invention herein disclosed can be made within the scope of what is claimed without departing from the scope or spirit of the invention.

What I claim as new and desire to secure by Letters Patent is:

1. In a car, a plurality of signal lamps of different colors, a press button in said car, means adapted to automatically light one of said lamps when said button is pressed and means adapted to automatically extinguish said lighted lamp and light another of said lamps when the velocity of said car is slackened, and to permit said last lamp to be lighted continuously during the time said car is at a standstill and means adapted to automatically extinguish said last lamp and light another of said lamps when said car has attained a predetermined rate of velocity.

2. In a car, a safety lamp, a caution lamp and a danger lamp, manual operative means in said car adapted to be actuated by a passenger for signaling the motorman of said car to stop, means adapted to automatically light said caution lamp when said passenger operates said manual operative means, and means adapted to automatically extinguish said caution lamp and light said danger lamp when said car has slackened its velocity and adapted to extinguish said danger lamp and light said safety lamp when said car has attained a predetermined rate of velocity.

3. In combination with a vehicle, a safety signal, a caution signal and a danger signal, a spindle rotatably connected to a rotatable part of said vehicle, a contact slidably mounted on said spindle, a governor fixed to said spindle and having an arm connected to said contact, a pair of safety terminals, a pair of caution terminals and a pair of danger terminals, respectively, adapted to be contacted by said contact, a pair of solenoids, a bar within each of said solenoids and having a conducting member connected to the adjacent ends of said bars, a pair of caution terminals and a pair of safety circuit terminals, respectively, adapted to be contacted by said conducting member, and manual operative means adapted to complete an electric circuit whereby one of said solenoids is adapted to draw one of said bars and disengage said safety circuit terminals and simultaneously electrically contact said caution terminals whereby said caution signal is adapted to be illuminated.

4. In combination with a vehicle, a safety signal, a caution signal and a danger signal,

a spindle rotatably connected to a rotatable part of said vehicle, and having a spring therearound, a contact slidably mounted on said spindle, a governor fixed to said spindle and having an arm connected to said contact, a pair of safety terminals, a pair of caution terminals and a pair of danger terminals, respectively, adapted to be contacted by said contact, a pair of solenoids, a bar within each of said solenoids and having a conducting member connected to the adjacent ends of said bars, a pair of solenoid terminals and a pair of safety circuit terminals, respectively, adapted to be contacted by said conducting member, manual operative means adapted to complete an electric circuit whereby one of said solenoids is adapted to draw one of said bars and disengage said safety circuit terminals and simultaneously electrically contact said caution terminals whereby said caution signal is adapted to be illuminated, said spring adapted to close said governor when the speed of said car is reduced whereby said contact is adapted to form electrical contact with said solenoid terminals whereby an electric circuit is completed and the other of said bars is drawn inwardly and said conducting member forms electrical contact with said safety signal circuit terminals.

5. In combination with a vehicle, a safety signal, a caution signal and a danger signal, a spindle rotatably connected to a rotatable part of said vehicle, a contact slidably mounted on said spindle, a governor fixed to said spindle and having an arm connected to said contact, a spring around said spindle and in engagement with said governor, a pair of safety terminals, a pair of solenoid terminals and a pair of danger terminals.

respectively, adapted to be contacted by said contact, a pair of solenoids, a pair of bars within said solenoids, respectively, and having a conducting member connected to the adjacent ends of said bars, a pair of caution terminals and a pair of safety circuit terminals respectively adapted to be contacted by said conducting member, manual operative means adapted to complete an electric circuit whereby one of said solenoids is adapted to draw said bars and disengage said conducting member from said safety circuit terminals and simultaneously electrically contact said caution terminals whereby said caution signal is adapted to be illuminated, said spring adapted to close said governor when the speed of said car is reduced whereby said contact is adapted to form electrical contact with said solenoid terminals whereby an electric circuit is completed through the other of said solenoids whereby said bars are drawn inwardly and said conducting member forms electrical contact with said safety signal circuit terminals and as the speed of said car is further reduced said governor is adapted to further close whereby said contact engages said danger terminals and said danger signal is illuminated.

6. In a car, a plurality of signal lamps of different colors, a press button in said car, means adapted to automatically extinguish one of said lamps when said button is pressed and to automatically light another of said lamps and means adapted to automatically extinguish said last lamp and light another of said lamps when the velocity of said car is slackened. 70
